(No Model.)

R. E. WILLIAMS.
REFLECTOR FOR LAMPS.

No. 365,215.

Patented June 21, 1887.

UNITED STATES PATENT OFFICE.

ROBERT E. WILLIAMS, OF DALLAS, TEXAS, ASSIGNOR OF ONE-HALF TO T. G. HAMMER, OF NEW ORLEANS, LOUISIANA.

REFLECTOR FOR LAMPS.

SPECIFICATION forming part of Letters Patent No. 365,215, dated June 21, 1887.

Application filed September 20, 1886. Serial No. 214,003. (No model.)

To all whom it may concern:

Be it known that I, ROBERT E. WILLIAMS, a citizen of the United States, and a resident of Dallas, in the county of Dallas and State of Texas, have invented certain new and useful Improvements in Reflectors for Lamps, &c.; and I do hereby declare that the following is a full, clear, and exact description of the invention, which will enable others skilled in the art to which it appertains to make and use the same, reference being had to the accompanying drawings, which form a part of this specification, and in which—

Figure 1 is a side elevation of my reflector adjusted to an ordinary lamp. Fig. 2 is a similar view of the same attached to a lamp and so adjusted as to adapt the lamp for student use. Fig. 3 is a back elevation of the reflector and its means of attachment, and Fig. 4 represents a plan view and cross-section of the attachment.

Like letters of reference indicate corresponding parts throughout the several figures.

My invention has relation to reflectors for lamps and to means for attaching the same; and it consists in the improved construction and combination of parts constituting the same, as will be hereinafter fully set forth.

In the accompanying drawings, A represents the reflector, which is in form an ellipsoidal shell provided near one end with an opening for the lamp chimney and at the other end with means for connecting it to a lamp. Said means consists of a flat bail, B, secured to the back of the reflector, through which passes a looped wire, C, bent in the plane of the loop into an arc which conforms to the

curvature of that portion of the surface of the reflector which is in a vertical line through said bail, the ends of said wire being attached to a collar, D, by passing the ends through holes in said collar, curving them around in a bead, H, and soldering them fast.

The wire loop fits sufficiently tight in the bail to hold the reflector in any desired position, and the collar turns freely enough to allow the reflector to be swung around the light to any desired place. The adaptability of the reflector to be tilted upon its attachment provides for its performing the office of a shade as well as of a reflector.

This reflector may be made of any desired material, glass or metal, and may be changed somewhat in shape, if desired.

Having thus fully described my invention, I claim—

In a reflector for lamps, the combination of a collar provided with a bead and having two holes through said bead, a looped wire the looped portion of which is curved and the ends of which are also curved and passed through the holes in said collar and rigidly secured within said bead, and a shell the upper end of which is provided with a hole and the lower with a bail for securing the same upon the curved portion of said loop.

In testimony that I claim the foregoing as my own I have hereunto affixed my signature in presence of two witnesses.

ROBERT E. WILLIAMS.

Witnesses:

ALEX. E. BOUCHE,
N. G. TURNEY.
